US0D1086146S

(12) **United States Design Patent** (10) **Patent No.:** **US D1,086,146 S**
(45) **Date of Patent:** **** Jul. 29, 2025**

(54) **COORDINATE INPUT DEVICE**

(71) Applicant: **Wacom Co., Ltd.**, Kazo (JP)

(72) Inventor: **Naoya Nishizawa**, Tokyo (JP)

(73) Assignee: **Wacom Co., Ltd.**, Kazo (JP)

(**) Term: **15 Years**

(21) Appl. No.: **29/819,854**

(22) Filed: **Dec. 17, 2021**

(30) **Foreign Application Priority Data**

Jun. 24, 2021 (JP) ..... 2021-013725 D

(51) **LOC (15) Cl.** **14-02**

(52) **U.S. Cl.**

USPC **D14/451**

(58) **Field of Classification Search**

(57) **CLAIM**

The ornamental design for a coordinate input device as shown and described.

DESCRIPTION

FIG. 1 is a front-top-left perspective view of a coordinate input device according to my new design;

FIG. 2 is a rear-top-left perspective view thereof;

FIG. 3 is a rear-bottom-right perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is top plan view thereof; and,

FIG. 9 is a bottom plan view thereof.

The broken lines in the figures depict portions of the coordinate input device that form no part of the claimed design.

1 Claim, 9 Drawing Sheets
